UNITED STATES PATENT OFFICE

2,334,568

APPARATUS FOR STARTING AND CONTROL-
LING ELECTRICAL DISCHARGE DEVICESHarold W. Lord, Schenectady, N. Y., assignor to
General Electric Company, a corporation of
New York

Application January 22, 1942, Serial No. 427,789

5 Claims. (Cl. 176—124)

My invention relates to apparatus for starting and controlling electric discharge devices employed on alternating current circuits. Although my invention is applicable to the starting and controlling of discharge devices of various forms, it has been particularly devised to be used with fluorescent lamps now coming into extensive use. Such lamps comprise a transparent tubular envelope containing mercury vapor at low pressure and having the inner surface of its side walls coated with a suitable phosphor which under the influence of an electric discharge through the mercury vapor produces fluorescence. The lamp electrodes which are mounted in the ends of the envelope are filamentary in form and are coated with a suitable electron emitting material. Such a lamp requires for its starting the application of a voltage impulse considerably higher than the voltage necessary to keep the lamp in operation after it has been started. Inasmuch as the voltage required to start such a lamp is materially less if the lamp electrodes are heated prior to the application of the starting voltage and since less injury is done to the lamp if its electrodes are preheated it has become common practice to heat the electrodes to the point of electron emission prior to the application of the starting voltage.

To avoid the delay incident to the preheating of the electrodes instant starting of such lamps has been effected by applying thereto a voltage sufficient to make them break down immediately even with cold electrodes. For that purpose use has been made of a high reactance step-up transformer designed to give the necessary high starting voltage but such apparatus has had the objection of being electrically inefficient and of being cumbersome, since it has poor material utilization, and accordingly is expensive to manufacture.

One object of my invention is to provide improved apparatus for producing a starting impulse for an electric discharge device operating on a lagging current circuit, the electrodes of which device are not preheated or are only partially preheated.

In accordance with my invention, briefly, I have provided apparatus which when connected between a discharge device and a source of alternating current supply will produce a voltage peak and will superpose it on the voltage wave supplied to the device, the maximum value of the voltage impulse thus produced being sufficient to cause the device to start without electrode pre-

heating. This apparatus, in part, functions as ballast impedance for the device.

My invention will be better understood from the following description taken in connection with the accompanying drawing and its scope will be pointed out in the appended claims.

Referring to the drawing, Fig. 1 is a circuit diagram illustrating one embodiment of my invention; Fig. 2 is a diagram showing the volt-ampere characteristic of a special form of reactor which I employ; Fig. 3 is a diagram of the voltage wave or impulse which I obtain; and Fig. 4 is a circuit diagram showing a modification.

In Fig. 1 the electric discharge device 1 is represented as a fluorescent lamp which, for example, may be a 40 watt lamp having a length of 48 inches and a diameter of 1½ inches such lamps being in common use at the present time. It has a tubular glass envelope containing mercury vapor at low pressure and a small quantity of neon or argon gas. The electrodes 2 are filamentary in form being wound in close coils and constructed of a refractory metal wire such as tungsten coated with a suitable electron emitting material such as barium oxide or strontium oxide. Since the electrodes are not provided with means for raising their temperature to the point of electron emission prior to the application of the starting voltage to the device as is commonly done, they are preferably constructed to have a very small mass whereby when a voltage impulse of sufficient intensity is applied to the device to make it break down without prior heating of the electrodes, the electrodes or portions thereof at least have their temperatures raised so quickly that little loss of the electron emitting material and only a very slight blackening of the adjacent ends of the envelope may occur. The two ends of each electrode are shown connected together in order that the operating current may be supplied to the electrode at both ends thereof. However, if desired the current may be supplied to the electrode from one end only.

The device which may have a voltage drop thereacross of 110 volts when running is connected to be energized from the source of alternating current supply 3 which may be a 60 cycle, 230 volt lighting circuit through the connections 4 and 5 and controlled by the switch 6. Arranged in one of the connections, for example 4, is the non-linear reactor 7 shown as comprising the three-legged laminated core 8 on the middle leg of which is the winding 9. The core may be built up of E-shaped laminations and bar laminations, adjacent E laminations being reversely arranged

in order to break the joints with the bar laminations in the usual and well known manner. The middle leg of each E lamination has a narrow transverse rectangular opening 10 punched therein, the openings in the several laminations forming the stack being in alignment and constituting an air gap, while the neck 11 at each end of the opening saturates through the major part of each half cycle of the applied voltage. Such an air gap is commonly termed a "bridged gap." A reactor such as is shown in Fig. 1 and described above has a volt-ampere characteristic like that represented at 12 in Fig. 2, the bend 13 in the curve marking the point at which saturation occurs in the necks 11.

Connected in shunt with the device 1 is reactive means comprising the reactor 14 and the capacitor 15 in series therewith. The reactance of the capacitor predominates; hence the net reactance of the reactive means is capacitive. The reactor 14 is shown as comprising a core having its middle leg provided with the air gap 16 and with the winding 17 thereon. The core may be built up of E-shaped laminations 18 and T-shaped laminations 19, adjacent laminations being reversely arranged to break the joints therebetween in the usual manner and being stacked to cause the air gap faces of the laminations to aline with each other.

It is stated above that the net reactance of the reactor 14 and the capacitor 15 is capacitive. The amount of capacitance provided by the capacitor is such that the reactors 7 and 14 and the capacitor 15 form a resonant circuit during those parts of each cycle of the applied voltage when the necks 11 of the reactor 7 are desaturated. By the saturation of the necks, the circuit is detuned until desaturation again occurs later in the cycle. Thus, twice in each cycle at approximately those times of maximum applied voltage a condition of resonance exists. At each of those times, therefore, the voltage across the shunt circuit, which is that applied to the device 1, is very materially increased and constitutes a peak. Actually the peaks occur slightly after the crest of the voltage wave of the source, the delay probably being due to the inductive effect of the reactor 14 and the iron losses therein.

In Fig. 3, I have shown at 22 the voltage wave of the source and at 23 the voltage wave applied to the device having the peaks 24 whose maximum value is ample to cause the device to break down without any preheating of its electrodes. The device having broken down continues to operate ballasted by the reactor 7 in the well known manner. The resonance condition no longer obtains and since the discharge in the device shunts the reactor 14 and the capacitor the energy loss in those members is relatively small.

Instead of employing the reactor 7 of the construction shown and described, one may, if desired, obtain the same result by the use of two separate reactors as shown at 27 and 28 in the modification comprising Fig. 4. The former is a high reactance reactor whose core forms a closed magnetic circuit which is adapted to saturate. Its winding 29 is connected in series with the winding 30 on the reactor 28 whose core has the air gap 31 therein. The core of the reactor 27 may be built of E-shaped laminations and bar laminations and the core of the reactor 28 may be built up of E-shaped laminations and T-shaped laminations. In this modification the reactor 27, since it saturates, functions like that part of the reac-

tor 7 which includes the necks 11; the reactor 28, since it has an air gap, functions like that part of the reactor 7 which includes the air gap 10. In the circuit shunting the device 1 are the reactor 14 like the corresponding reactor of Fig. 1 and the capacitor 15 also like the corresponding capacitor in that figure. The three reactors and the capacitor in this modification function in cooperation to produce a voltage peak such as that and in the manner already described above.

Although the voltage peaks produced with my invention are sufficient to make the device break down with cold electrodes one may, if desired, connect the shunt circuit to the device in such a manner that the current of that circuit passes through the electrodes thereby producing a certain amount of heating thereof. Such an arrangement is shown in the modification comprising Fig. 4 where the electrodes are included in series with the several reactors and the capacitor.

I have chosen the particular embodiments described above as illustrative of my invention and it will be apparent that various other modifications may be made without departing from the spirit and scope of my invention which modifications I aim to cover by the appended claims.

What I claim as new and desire to secure by Letters Patent of the United States is:

1. In combination, a source of alternating current supply, an electric discharge device, a first reactive means connected in series with said device across said source, and a second reactive means comprising an inductive and a capacitive member, the net reactance of which members is capacitive, connected in shunt with said device, said first reactive means comprising a part constructed to saturate during parts of both half cycles of said current and said first and second reactive means being constructed to form together a circuit which resonates when said part is desaturated.

2. In combination, a source of alternating current supply, an electric discharge device, reactive means connected in series with said device across said source and reactive means connected in shunt with said device, said first mentioned reactive means having a core part constructed to saturate during parts of both half cycles of said current and a core part having an air gap, all of said reactive means together comprising a resonant circuit when said saturable core part is desaturated.

3. In combination, a source of alternating current supply, an electric discharge device, a reactor connected in series with said device across said source and reactive means connected in shunt with said device, said reactor having a core, one part of which is constructed to saturate and another part of which has an air gap therein, and said reactor and said reactive means comprising a resonant circuit when the first mentioned part is desaturated.

4. In combination, a source of alternating current supply, an electric discharge device, a reactor connected in series with said device across said source and reactive means connected in shunt with said device, said reactor having a core including a part provided with a bridged gap at which saturation occurs and a winding on said part, the reactance of said reactive means being such that resonance occurs during those parts of the applied voltage wave at which said bridged gap is desaturated.

5. In combination, a source of alternating cur-

rent supply, an electric discharge device, a first reactive means connected in series with said device across said source, and a second reactive means comprising an inductive and a capacitive member, the net reactance of which members is 5 capacitive, connected in shunt with said device, said first reactive means having a plurality of

restricted parts constructed all to saturate during parts of each half cycle of said current, said first and second reactive means forming together a circuit which resonates when said parts are desaturated.

HAROLD W. LORD.
